UNITED STATES PATENT OFFICE.

HARRY R. VAN DEVENTER, OF NEW YORK, N. Y., ASSIGNOR TO DUBILIER CONDENSER CORPORATION, OF NEW YORK, N. Y., A CORPORATION OF DELAWARE.

VARIABLE CONDENSER.

Application filed April 23, 1923. Serial No. 634,097.

This invention relates to condensers, and more particularly it relates to variable condensers.

An object of my invention is to provide a condenser in which the adjustment of the relative positions of the condenser elements is accomplished with the minimum of friction of the parts.

Another object of my invention is to make a condenser structure in which the condenser elements are resiliently held in close contact for that portion of their surfaces that are in operative relationship to each other, at any given setting of the condenser.

A further object of my invention is to provide a condenser so constructed that the means for effecting the adjustments can be located on either side of the housing, thus making the condenser adapted to a wide variety of uses.

A still further object of my invention is to show how to construct a variable condenser that is sturdy, and capable of use by unskilled persons for long periods of time without the necessity of repair or replacement.

In the drawings:—

Figure 1 is a view in longitudinal section of my device taken on a plane passing through the axis of the rotor shaft;

Fig. 2 is a bottom plan view of my variable condenser with part of the cover plate broken away to more clearly show the position of the parts;

Fig. 3 is a view in cross section of my device taken on the line 3—3 of Fig. 1, looking in the direction of the arrows;

Fig. 4 is a detail view in perspective of the retaining spring;

Fig. 5 is a detail view in perspective of the rotor;

Fig. 6 is a view in side elevation of my variable condenser with a portion of the casing broken away, showing the adaptation of the condenser wherein an extension shaft is mounted on the cover plate side;

Fig. 7 is a detail view in perspective of the adjustable element of my condenser.

I have illustrated my invention as comprising a casing 1 of some suitable insulating material such as hard rubber or bakelite. The casing 1 is provided with a downwardly extending annular flange 2 which forms one wall of the housing for the variable condenser. The casing 1 has an upwardly extending cylindrical portion 3 within which is journaled

a metallic shaft 4. The metallic shaft 4 is formed with apertures at either end thereof. As shown in the drawings, an aperture 5 extends the entire distance through the center of the shaft and is screw-threaded. The lower end of the aperture 5 is slightly widened, as indicated at 6, thereby forming a conical seat 7.

Formed on the shaft 4, and preferably integrally made therewith, is a shoulder 8, which I have shown as of square configuration, over which is adapted to fit an aperture 9 centrally formed in a rotor 11 of insulating material. The rotor 11 is provided with a slot 12 therein which is set at an angle to the radii of the rotor. The slot 12 is provided with beveled edges 13. The fit between the aperture 9 and the shoulder 8 of the shaft 4 is not a tight fit, but the rotor is adapted to float on the shoulder 8 and be capable of ready movement in the direction of the axis of the shaft 4.

Mounted against the upper interior wall of the casing 1 is an annular fixed condenser plate 14 preferably formed of metallic foil. The condenser plate 14 fits into a recess 15 formed in the casing, and a metallic eyelet 16 is adapted to pass through the sheet or plate of metallic foil 14 and to make contact therewith, through a holding contact piece 17. The eyelet 16 is riveted in place to make the connection permanent. Covering the conducting sheet 14 is an insulating sheet of mica 18 which is in close relationship to the conducting foil 14 and is preferably fixed thereto by a suitable adhesive.

The flexible condenser element comprises a flexible strip of metal 19 of annular conformation, see Fig. 7. This metallic strip has a convolute intension which tends to spring it out, as shown in Fig. 7. One edge of the free end of the flexible element 19 is upturned, as indicated at 20. The flexible element 19 is provided with a relatively wide neck 21 extending into an aperture 22 formed in the casing 1. An eyelet 23 makes contact with the flexible element 19 through a holding contact member 24. The eyelet 23 is riveted in place and makes permanent electrical connection with the flexible sheet 19.

The free end of the flexible element 19 is adapted to slide through the slot 12 in the rotor 11. The rotor 11 is spring pressed in the direction of the fixed element of the condenser comprising the metallic foil 14 and

the mica sheet 18. The rotor 11 compresses that portion of the contacting surfaces of the fixed and adjustable elements which are adapted to be operative for any given capacity adjustment. In order to maintain the rotor 11 in this spring pressed relationship to the condenser elements, I have provided a spring member 25 having spring arms 26 which are upwardly intensioned, as indicated 10 in Fig. 4. The spring member 25 is mounted over a downwardly projecting annular flange 27 of the shaft 4. A washer 28 is fitted over the flange, and the flange 27 is then riveted to hold the spring member 25 firmly 15 between the washer and the shoulder 8 of the shaft 4. This construction holds the spring member 25 firmly in place and permits the upper ends of the spring arms 26 to contact against the rotor 11 to urge it upwardly. 20 The arms 26 are of such a length that the pressure is exerted on the rotor 11 at a point between the center of the rotor and its circumference, thereby insuring that the maximum degree of pressure shall be exerted on 25 the annular fixed and flexible condenser elements. If pressure were exerted at the center or periphery of the rotor, its effect would not be so readily transmitted as is the case where it is exerted directly adjacent to the 30 main surface area of the condenser elements.

A turning knob 31 is attached to the shaft 4 by means of a screw 32 fitting into the screw-threaded aperture 5 of the shaft, whereby the shaft may be rotated. A pointer 33 is keyed to the turning knob 31, and a shim washer 34 is mounted on the upper face of the upwardly projecting portion 3 of the casing 1. The shim washer 34 is depressed, as indicated at 35, into a depression formed 40 in the portion 3 of the casing. Thereby the shim washer 34 is prevented from rotation, yet the knob and pointer 33 can easily turn. A shim washer 37 is provided on the interior face of the casing 1. The shim washer 37 45 is depressed, as indicated at 38, into a depression 39 formed in the upper interior wall of the casing 1. These two shim washers have been found to add greatly to the sturdiness of the construction and the strength of the 50 general shaft assembly, preventing undue play after long use.

Fitting over the lower surface of the casing is an insulating cover plate 40, held to the casing 1 by means of drive screws 41. 55 An aperture 42 is provided in the cover plate opposite the shaft 4, and apertures 43 are formed opposite the eyelets 16 and 23. The cover plate 40 forms with the rotor 11 a recess within which the flexible member 19 60 may be housed when it has passed through the slot 12 of the rotor 11.

In operation, by turning the knob 31 in a clockwise direction, the rotor 11 is caused to move to pick up a portion of the flexible element 19 to vary the capacity of the condenser. 65

By reason of the bevelling of the edges 13, the picking up of the flexible element 19 is greatly facilitated, because the friction between the flexible element and the rotor is reduced to a minimum by reason of the sharp 70 entering angle presented to the surfaces. To increase the facility with which the rotor picks up the flexible element 19, the slot 12 is set at an angle to the radii of the rotor 11. This tends to make the outer edge of the rotor 75 11 have a slightly greater initial engagement with the flexible element 19, and this edge therefore operates as a starting wedge, thus further facilitating the picking up of the flexible element 19. Moreover, one edge 20 of 80 the flexible element 19 is upturned, which aids the rotor 11 in picking up the elements, and by reason of the fact that the flexible element is given a convolute intension in its manufacture and retains this convolute intension in the assembled device, the flexible element 19 has a 85 tendency to spring out through the slot 12 in the rotor.

By rotating the rotor, the flexible plate 19 is subjected to a "picking up" and "laying 90 down" operation on the fixed element whereby the capacity of the condenser is varied. The casing 1 is provided with a scale which co-operates with the pointer 33 to indicate the adjustment effected. 95

The utility of the apertured shaft 4 will be apparent from an inspection of Fig. 6, in which the condenser is shown mounted on the interior of a box 51. An extension shaft 52 is screw-threaded, through the aperture 42 in 100 the cover plate 40, into the screw-threaded aperture 5 in the shaft 4. The extension shaft 52 is provided with a conical seat 53 which engages the conical seat 7 formed in the shaft 4. A knob 54 is screwed by means of a screw 55 into the shaft 52, and a suitable scale may be provided for co-operation with the knob to indicate the adjustment of the condenser. Binding posts 56 are provided with extension 105 screws 57 which pass through the eyelets 16 and 23 and through the apertures 43 in the cover plate 40. It is thus apparent that the utility of the condenser is largely increased by the construction which permits it to be used 110 in the reverse position if desired. 115

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims. 120

I claim:

1. A variable condenser comprising, a fixed element, an adjustable element, a shaft, a rotor floatably mounted on and adapted to turn with the shaft, a shoulder on the shaft, a wash- 125 130

- er on the shaft, a plurality of retaining 5 springs for exerting pressure on the rotor mounted between the washer and the shoulder, and means for holding the retaining spring between the washer and the shoulder.
2. A variable condenser comprising, a casing, relatively adjustable condenser elements within the casing, a shaft having a screw-threaded aperture therein at either end, a 10 cover plate for the casing having an aperture communicating with the shaft, and means adapted to engage with the screw-threads of the apertures, whereby the condenser may be adjusted for compression from either side.
- 15 3. A variable condenser comprising, a casing, a fixed element, an adjustable element, a rotor having a slot therein through which the adjustable element is adapted to slide, a shaft upon which the rotor is mounted, means attached to the shaft for resiliently pressing the rotor against the fixed element, a knob to 20 rotate the shaft, a pointer moving with the knob,
- a shim washer on the casing held against rotation by an indented portion fitting into a depression in the casing, and another shim 25 washer on the interior of the casing and held against rotation by an indented portion fitting into a depression in the casing.
4. A variable condenser comprising, a casing, a fixed element, an adjustable element, a 30 rotor having a slot therein through which the adjustable element is adapted to slide, a shaft upon which the rotor is mounted, means attached to the shaft for resiliently pressing the rotor against the fixed element, means exterior of the casing to rotate the shaft, a shim washer on the casing held against rotation by an indented portion fitting into a depression in the casing, and another shim washer on the 35 interior of the casing and held against rotation by an indented portion fitting into a depression in the casing.

In testimony whereof I affix my signature.
HARRY R. VAN DEVENTER.
